Howard Rowson*

UNITED STATES PATENT OFFICE.

GEORGE PRIFOLD, OF LINWOOD, PENNSYLVANIA, ASSIGNOR TO THE CONGOLEUM COMPANY, OF PHILADELPHIA, PENNSYLVANIA, A CORPORATION OF PENNSYLVANIA.

PROCESS OF PRINTING RUGS.

1,191,825.

Specification of Letters Patent.

Patented July 18, 1916.

Application filed February 29, 1916. Serial No. 81,188.

To all whom it may concern:

Be it known that I, GEORGE PRIFOLD, a citizen of the United States, and a resident of Linwood, county of Delaware, State of 5 Pennsylvania, have invented certain Improvements in Processes of Printing Rugs, of which the following is a specification.

The object of my invention is to reduce the number of blocks used in printing rugs, 10 The invention is particularly adapted for printing designs in paint colors on coated materials.

Heretofore, it has been the practice to make a set of independent blocks for each 15 end of the rug which includes the end border design and another set of blocks for the center having the continuations of the side borders of the rug. These rugs are made by a continuous process in which the material is intermittently moved under a series 20 of blocks, each having an independent vertical movement to and from the material.

In the accompanying drawings: Figure 1 is a diagrammatic inverted plan 25 view illustrating a printing block showing the design thereon for printing the two end borders of a rug; Fig. 2 is a diagrammatic inverted plan view of a block having a design thereon for printing the body 30 of the rug and continuations of the side borders; Fig. 3 is a diagrammatic view showing a strip with a series of rug designs printed thereon, and Fig. 4 is a view of a completed rug.

35 While, in practice, each block is made in a number of sections and the designs of the sections are formed by dots or lines, I have shown the figures on the blocks, as well as the design, in solid colors to avoid unnecessary details.

Referring to the drawings, *a* and *b* are 40 two rectangular printing blocks used in a machine of the type illustrated in the Letters Patent granted to William H. Waldron, for a block printing machine, No. 1,145,821, July 6, 1915. The block *a* has a design formed thereon consisting of the two end borders *c* and *c'* which include the short sections of the side borders and in addition to this there 45 is a design *d* of any suitable type forming

a portion of the body design of the rug. The block *b* has continuations *c²* of the side borders and also has the body designs *d'*, which are spaced so as to conform to the body design *d*.

55

There are two blocks used for each color and the number of blocks will depend entirely upon the number of colors to be used in printing a series of rugs. The material *x*, Fig. 3, is in the form of a long strip and, 60 in the present instance, consists of a felt piece coated with suitable material to form a printing surface, although it may have a woven base, such as ordinary oilcloth, without departing from the essential features of 65 the invention.

The material is passed intermittently through a machine of the type above described and the blocks *a* and *b* are secured to the carriers of the machine and the movement of these blocks is controlled by mechanism so timed that as the material passes through the machine the proper design will be printed on the material, such as that illustrated in Fig. 4, one design following another, as shown in Fig. 3. After the printing is finished, the material is dried in any suitable apparatus and is cut into sections 70 to form rugs, as illustrated in Fig. 4.

In the present type of machine, the width 75 of the block is limited to about one foot, six inches, and two border designs each eight inches wide can be formed on such a block. The width of the border will be defined by the width of the block.

85

I claim:

The process herein described of printing bordered rugs, on continuous strips, said process consisting in forming the end border of two adjacent rugs on the same block; 90 forming the design of the body portion of the rug, including sections of the side borders, on another block, then making the impressions on the strips of material with both blocks so that a series of complete rugs 95 will be printed on the strip; and finally severing the strip on the lines of the rug designs, making individual rugs.

GEORGE PRIFOLD.
